United States Patent Office

Des. 220,680
Patented May 11, 1971

220,680

BOTTLE

Van H. Neher, Mauricetown, N.J., assignor to Wheaton
Glass Company, Millville, N.J.

Filed Feb. 18, 1970, Ser. No. 21,477

Term of patent 14 years

Int. Cl. D9—01

U.S. Cl. D9—62

Fig. 1

Fig. 3

FIG. 1 is a front elevational view of a bottle showing my new design;

FIG. 2 is a rear elevational view;

FIG. 3 is an elevational view looking from the right of FIG. 1; and

FIG. 4 is a sectional view thereof taken on the line 4—4 of FIG. 1.

I claim:

The ornamental design for a bottle, as shown.
